Primary Examiner — Ian Simmons*Assistant Examiner* — Yolanda Robinson(74) *Attorney, Agent, or Firm* — Kusner & Jaffe(57) **CLAIM**

The ornamental design for an outer tie rod end, as shown and described.

DESCRIPTION

FIG. 1 is a top rear isometric view of an outer tie rod end, showing our design;

FIG. 2 is a bottom front isometric view thereof;

FIG. 3 is a rear view thereof;

FIG. 4 is a front view thereof;

FIG. 5 is a right side view thereof;

FIG. 6 is a left side view thereof;

FIG. 7 is a bottom view thereof; and,

FIG. 8 is a top view thereof.

The broken lines shown in the drawings illustrate portions of the outer tie rod end that form no part of the claimed design.

1 Claim, 5 Drawing Sheets(56)
